UNITED STATES PATENT OFFICE.

HENRY ERICSSON, OF CHICAGO, ILLINOIS.

FORM FOR CONCRETE FLOORS AND THE LIKE.

1,191,881.

Specification of Letters Patent. Patented July 18, 1916.

Application filed May 26, 1910. Serial No. 563,502.

To all whom it may concern:

Be it known that I, HENRY ERICSSON, a citizen of the United States, residing at Chicago, in the county of Cook and State of Illinois, have invented certain new and useful Improvements in Forms for Concrete Floors and the like, of which the following is a description.

My invention relates to means adapted to 10 be arranged in the space to be provided with the floor, adapted to receive the concrete and support the same in position until it has fully hardened or set, after which my device may be removed leaving the floor in position.

The object of my invention is to provide 20 a simple, convenient and efficient device of the kind described, adapted to form a floor of the greatest possible strength with the smallest amount of material.

To this end my invention consists in the 25 novel construction, arrangement and combination of parts herein shown and described, and more particularly pointed out in the claims.

In the accompanying drawings wherein 30 like or similar reference characters indicate like or corresponding parts: Figure 1, is a longitudinal section of a floor showing my forms in position, taken substantially 35 on line 1—1 of Fig. 2. Fig. 2, is a section taken substantially on line 2—2 of Fig. 1. Fig. 3, is a bottom plan view of the same. Fig. 4, is a detail of a convenient latch or 40 bar for securing the elements of my device together. Fig. 5, is a longitudinal section of an extensible form of my device taken substantially on line 5—5 of Fig. 6. Fig. 6 is a section taken substantially on line 6—6 45 of Fig. 5.

In the form shown in the drawings 1—1 are I beams arranged in the usual or any preferred manner to be embedded in the floor. A plank or board 2 of suitable width 45 is suspended below each I beam by hook-bolts 3—3 or other convenient means for the purpose. As shown a strip of wood or other material 4 is arranged at suitable intervals transversely of the board 2 so as 50 to prevent its warping or splitting when in use and the hook-bolts 3—3 pass through the strips 4, thereby distributing the strain of the bolts across the entire width of the

board 2. A pair of inclined strips 5—5 are secured to the upper face of the boards 2 at each edge, each strip being of suitable width to reach to the underside of the main body of the floor. When thus arranged the several elements of my device are positioned between the I beams as shown in Fig. 1, with the ends of each element resting upon the upper edge of the strips 5.

In the construction shown each element consists of a plate 6 of steel or other suitable material of sufficient length to extend across the space between the strips 5—5 upon adjacent I beams. The plates 6 are preferably curved transversely in any desired manner to suit the peculiar conditions of the floor to be constructed. As shown the edges of each plate are curved to form an ogee so arranged that the central portion of the plate will present the form of a slightly flattened arch with the extreme marginal edges 7 and 8 of the plates bent outward in a common plane to form the base of the arch.

When in operative position the edges 7 and 8 of the elements 6 preferably overlap slightly, to close the space between the adjacent elements, and if desired a portion as at 9 upon one of the margins as 7 may be set-off vertically the thickness of the plate so that the upper surface of the marginal portions of the combined elements when in use will be flush. When thus constructed the marginal portions of the elements operate to gage the spacing of the elements horizontally. They also indicate or gage the relative vertical positions of the elements. In the preferred form suitable means are provided for rigidly maintaining the curved form of the element. As shown the extreme ends of each element are closed with a suitable inclined end 10 to which the sheet 6 is rigidly attached by screws, nails or other fastening means 25 and a series of suitable frames or partitions 11 are spaced at substantially equal distances along the element and rigidly secured to the sheet 6 the same as the ends 10 to maintain its several parts in proper relation and prevent any spreading or twisting of the elements when the concrete filling is applied. In the preferred construction shown, a bar 12 of wood or other suitable material is provided for each

straight edge of each element and rigidly secured thereto in any desired manner as by the screws, nails or other fasteners 26 to prevent the elements bending longitudinally when in service. Suitable means are 5 preferably provided to rigidly connect the adjacent elements together when in operation. In the form shown a plurality of latches or bars 14 are provided for this 10 purpose. One end of each bar 14 is shown pivotally attached to a partition 11 by a screw or bolt 15 and the opposite end of the bar 14 is notched as at 16 so that when the 15 elements are in position the notched end of the bar 14 may be engaged with a screw or bolt 17 upon the partition of an adjacent form to positively space the elements and hold the edges firmly in contact when in operation.

20 In the form shown in Figs. 5 and 6 an extension 18 is provided upon each element formed to snugly fit upon its exterior and telescope or slide longitudinally thereon so as to control the total length of the element 25 which is thus constructed of two substantially similar parts. The extension 18 is substantially of the same form and construction and is provided with an inclined end or closure 19 at its outer end, substantially 30 the same in all respects as the main portion of the elements hereinbefore described. The frames or partitions 11 are however not usually required except where the extensions are of considerable length as 35 the curved form of the extensions are maintained by their engagement with the main body of the element. In this form a temporary support 20 is provided to hold the end of the main element in position and the 40 extensions 18 rest upon and are supported by the strip 5 and the main element jointly. In operation the elements are arranged in the space between the beams 1—1 as hereinbefore described and as shown in Figs. 1 and 45 5. One or more reinforcing rods 21—22 are positioned in the depression between the elements preferably with one end of each rod attached to the upper flange of a beam as shown after which the concrete is filled in 50 around the rods to the proper height above the elements and its upper surface leveled off and smoothed or otherwise finished as desired and allowed to set or harden after which the supports 20 and the boxing at 55 each beam are taken down releasing the elements and permitting them to be readily removed, leaving a floor consisting of a series of arches extending between the beams, with suitable reinforcing means positioned in the 60 bases of the arches and attached to the beams.

Having thus described my improvement it is obvious that various immaterial modifications may be made in my device without departing from the spirit of my invention,

hence I do not wish to be understood as limiting myself to the exact form or construction shown.

What I claim as new and desire to secure, by Letters Patent is:

1. A device of the kind described, comprising contiguous transversely curved two part elements and a strip at each edge of each of said elements projecting laterally thereof and adapted to coöperate with a corresponding part upon a similarly formed element to close the space between adjacent elements and a longitudinal brace rigidly secured to each of said strips in combination with a plurality of partitions extending across each element and rigidly secured thereto, and means coöperating with said brace to rigidly connect the contiguous elements. 70

2. A device of the kind described, comprising contiguous transversely curved two part elements and a strip at each edge of each of said elements projecting laterally thereof and adapted to coöperate with a corresponding part upon a similarly formed element to close the space between adjacent elements and a longitudinal brace rigidly secured to each of said strips, in combination with a plurality of partitions extending across each element and rigidly secured thereto, and means attached to said partitions coöperating with said braces to rigidly connect contiguous elements. 90

3. A device of the kind described, comprising contiguous transversely curved sheet metal elements, a strip at each edge of each of said elements formed integrally therewith, projecting laterally therefrom and adapted to coöperate with the corresponding part of a similarly formed element to close the space between adjacent elements, in combination with a plurality of partitions extending across each element and rigidly secured thereto and a partition at each extremity of the element, a longitudinal brace rigidly secured to each of said strips, and means for rigidly locking the elements together. 100

4. A device of the kind described, comprising a transversely curved two part element and a strip at each edge of said element projecting laterally thereof and adapted to coöperate with a corresponding part upon a similarly formed element to close the space between adjacent elements and a longitudinal brace rigidly secured to each of said strips, in combination with means for rigidly maintaining the form of said element transversely and means for rigidly locking said elements together. 115

5. A device of the kind described, comprising a transversely curved two part element and a strip at each edge of said element projecting laterally thereof and adapted to coöperate with a corresponding part upon a similarly formed element to close the space 125 130

between adjacent elements, in combination with a plurality of transverse partitions and longitudinal braces each rigidly attached to said element and adapted to jointly maintain 5 the form of said element both longitudinally and transversely, and means upon said partitions adapted to coöperate with said braces to rigidly lock two of said elements together.

In testimony whereof, I have hereunto signed my name in the presence of two sub- 10 scribing witnesses.

HENRY ERICSSON.
